UNITED STATES PATENT OFFICE.

HALCOLM ELLIS, OF EAST ORANGE, NEW JERSEY.

MACHINE FOR CALCULATION AND PRINTING THE RESULTS OF SAID CALCULATIONS.

1,136,321.

Specification of Letters Patent. Patented Apr. 20, 1915.

Application filed October 3, 1912. Serial No. 723,756.

To all whom it may concern:

Be it known that I, HALCOLM ELLIS, a citizen of the United States, residing at East Orange, in the county of Essex and State of New Jersey, have invented new and useful Improvements in Machines for Calculation and Printing the Results of Said Calculations, of which the following is a specification.

10 The object of this invention is to provide a simple mechanism in an adding and listing machine by which the amount may be printed and at the same operation deducted from the amount previously registered on 15 the accumulator wheels. This end is attained by having each numeral key set two independent stops for limiting the travel of the actuators when operated, one set of stops being in correspondence with the numbers 20 on the keys and which limit the travel of the actuators and set the printing type in accordance with the numbers on the keys depressed and the other set of stops being such as to limit the travel of the actuators 25 after a movement equal to the complement of the numbers on the keys depressed, and a selective device by which the actuators may be made to engage either set of stops at the will of the operator so that the 30 machine will add the number set on the keyboard when engaging one set of stops and add the complement of the number set up on the keyboard when engaging the other set of stops, the type for printing the amount 35 being regulated in its position in either case by the first set of stops. This mechanism is shown and illustrated in connection with the machine known as the "Ellis adding-typewriter," which is fully set forth 40 in detail in my British Patent No. 28253 of Dec. 28, 1908.

A detailed description of the device is as follows, reference being had to the drawings in which—

45 Figure 1. is a longitudinal vertical section with parts in the normal position of rest. Fig. 2 is a similar section to Fig. 1. with the parts just at the position for releasing the printing sectors. Fig. 3. is a view of the subtracting key showing its immediate connecting devices. Fig. 4. is a front view of the keyboard showing the lateral arrangement of the parts and also a front view of the subtracting key and its connecting mechanism. Fig. 5. is a detailed view of the

piece R⁵³. Fig. 6. is a detailed view of the piece R⁵⁰ showing its connecting piece R⁵⁶.

The general operation of this machine is in all respects similar to the machine shown in my previously referred to application and similar letters of reference refer to similar parts.

The keys K⁵⁹ being depressed are held down by the latches 52^K (Fig. 4) and each key K⁵⁹ has two stop pins, a lower one K²³ and an upper one K²⁴, and the springs K⁸⁰ tend to raise the keys K⁵⁹. These stops K²³ and K²⁴ extend through the order plate 60^K. Mounted on the order plate 60^K is an irregular piece K⁷¹, mounted to slide horizontally on studs 18^K, 19^K. The upper side or edge of the piece K⁷¹ is arranged with a series of steps for engaging the stops K²⁴ when in their depressed position and these steps are arranged vernier fashion so that the extreme righthand one in the drawing will move a distance of one pitch or tooth of the actuator rack before engaging the stop K²⁴. The second step will move a distance of two pitches or teeth and the last step a distance of nine pitches or teeth. The function of the piece K⁷¹ will be more fully explained in connection with other mechanism.

The actuators of the adding wheels A⁵⁶ consist of the sliding racks R⁵⁰ having teeth on their upper and lower edge for engaging two sets of accumulators and are made to slide over the bar R⁹² at the rear end and over the bar K³ at the forward end. The rack R⁵⁰ has no direct means for engaging the stops K²³ and K²⁴. Its form is shown in Fig. 6. Parallel with the rack R⁵⁰ and sliding over the same bars R⁹² and K³ is another sliding piece R⁵³, shown in detail in Fig. 5. This piece R⁵³ has a series of steps at its forward end arranged vernier fashion to engage the stop pins K²³ when the same are depressed. The first step on the piece R⁵³ engages the stop pin K²³ on the first key on the keyboard and permits the piece R⁵³ to move to the rear of the machine a distance equal to one pitch or tooth of the rack R⁵⁰. The second step engages the stop pin K²³ on the second key of the system K⁵⁹ and permits the piece R⁵³ to move a distance of two teeth of the rack R⁵⁰, etc., each step permitting the slide R⁵³ to move one tooth farther than the preceding one in a rearward direction. This sliding piece R⁵³ also carries a slot on its lower edge for engaging the piece R¹⁴.

which operates the crank lever R^{45} which swings on the shaft R^1 and through the connecting rod P^{53} controls the setting of the type sectors P^{54} . The restoring bar R^{45} is in the form of a bail and is secured to the shaft R^1 and swings from the position shown in Fig. 1. to the position in Fig. 2. carrying with it the bar R^{51} , and spring R^{80} extending from the bar R^{51} to a vertically projecting horn on the rack R^{50} and when R^{45} is in the position shown in Fig. 2. the spring R^{80} tends to move the rack R^{50} to the rear of the machine. Mounted on the crank lever R^{45} is the alining sector R^{52} and the spring R^{81} extending from the bar R^{51} to the pin at the forward end of the alining sector R^{52} tends to swing the crank lever R^{45} in the same direction as the restoring bar R^{45} and by means of pin R^{14} engaging the slot in the lower side of the sliding piece R^{53} tends to move R^{53} in a rearward direction.

Referring to Fig. 6. there will be seen the piece R^{56} of irregular shape which is pivoted on the sliding rack R^{50} and a small spring R^{82} tends to keep the piece R^{56} in its lowered position. The piece R^{56} has a rack cut on its upper side at the forward end and a small lip on its lower side for engaging the pin R^{17} in the sliding piece R^{53} .

Mounted on the pivot 18^K is a segment rack K^{72} having an upwardly extending arm carrying a pin 20^K which engages a vertical slot in the piece K^{73} which in turn is secured to the piece K^{71} .

A small arm R^{57} is secured to a sleeve R^{31} which is free to turn upon the shaft T^2 . The forward end of the piece R^{56} pivoted to R^{50} rests on the upper end of the small arm R^{57} and R^{57} can assume either of two positions—that shown in Fig. 1. and that shown in Fig. 2. the normal position being that shown in Fig. 1. and the position shown in Fig. 2. being the position assumed when the subtracting key 70^K is depressed and the piece 72^K moves the piece 74^K (Fig. 3) and so turns the sleeve R^{31} . The normal position of the piece R^{57} as shown in Fig. 1. is maintained by the pressure of the piece R^{56} on its upper end which pressure is due to the spring R^{82} .

The mechanism for causing the piece R^{57} to assume the position shown in Fig. 2. is shown in Fig. 3. 70^K is the subtracting key the lower end of which is supported by the bracket 71^K secured to the underside of the keyboard and the spring K^{84} tends to hold the keystem 70^K in its elevated position. This key 70^K is made in the usual form employed in this machine for the operation keys such as total and subtotal keys, and is provided with a notch "a" on its rear edge. The latch piece 72^K is pivoted to the side frame B^{47} at K^{22} and has a lip "b" for engaging the notch "a" in the keystem 70^K . A pin 15^K in the lower end of the latch 72^K engages a slot in the upper end of the piece

74^K which is made fast to the sleeve R^{31} . When the key 70^K is depressed the lip "b" engages the notch "a" through the action of the spring K^{86} and the piece 74^K is moved from the position shown in Fig. 3. toward the left and the arm R^{57} moves from the position shown in Fig. 1. to the position shown in Fig. 2. and is retained in this position until the machine performs its complete cycle of operations which are determined by the rotation of the shaft O^1 through an angle of about sixty degrees and its return to its normal position. The speed of rotation of this shaft O^1 is regulated by the governor D^{47} (see Fig. 3.) and the arm 51^D is swung from the position shown in Fig. 3. to a position about vertical in the direction indicated by the arrow and on the return stroke the trigger 55^D pivoted on the end of the arm 51^D engages the turned over lip "c" of the piece 72^K and restores the piece 72^K to the position shown in Fig. 3. thereby releasing the key 70^K disengaging the lip "b" from the notch "a" and also restores the piece 74^K to its normal position and incidentally the arms R^{57} to the position shown in Fig. 1. The pin D^{12} serves to disengage the trigger 55^D from the lip "c" on the piece 72^K leaving the piece 72^K free to engage the key 70^K when the same is again depressed. The engagement of the trigger 55^D with the lip "c" on the piece 72^K is caused by the spring D^{45} maintaining the trigger 55^D in a position to engage the lip "c" while the trigger 55^D is making its upward stroke.

In describing the operation of this device I will first consider the relative position of the parts when the machine is to perform the function of addition. The key 70^K being in its elevated position, the arm R^{57} will be in a lowered position as shown in Fig. 1. and the piece R^{56} pivoted to the rack R^{50} will engage by means of the small lip on its lower side the pin R^{17} with a consequence that when the restoring bar R^{45} is moved in a rearward direction the rack R^{50} and the piece R^{53} will move solidly together as one piece and the travel or movement of these two pieces will be determined by the extent of travel permitted the piece R^{53} by the stops K^{23} and all functions and movements of the machine will be in all respects similar to a regular adding machine of this type. The type sector P^{54} will move in unison with the sliding pieces R^{53} and the rack R^{50} . A complete description of these operations is found in my British Patent No. 28253 of Dec. 28, 1908.

To cause the machine to subtract, first depress the amount to be subtracted on the keys K^{59} of the keyboard; next the key 70^K is depressed and the mechanism shown in Fig. 3. causes the arms R^{57} to raise the piece R^{56} until the teeth on the upper edge thereof engage the teeth of the segment K^{72} and the

small lip on the lower side of R^{56} disengages the pin R^{17} in the piece R^{53} . When the restoring bar 45^R moves to the position shown in Fig. 2, the spring R^{80} will move the piece R^{58} to the rear until the steps on the upper side of the piece R^{53} come in contact with the stops K^{23} on the keys K^{59} which are depressed and the piece R^{53} will cause the type sector P^{54} to present a type for printing that will correspond to the depressed key K^{59} . At the same time the spring R^{81} will move the rack R^{50} to the rear; the piece R^{56} being secured thereto and its teeth in engagement with the segment K^{72} will turn K^{72} and through the pin 20^K move the slide K^{71} in a forward direction until one of its steps engage the stop K^{24} on the depressed key K^{59} . The distance from the center of the pivot 18^K to the teeth on the segment K^{72} being the same as the distance from the center of the pivot 18^K to the pin 20^K the distance traveled by the rack R^{50} and the sliding piece K^{71} will be the same but in opposite directions, and the steps on the piece K^{71} are arranged vernier fashion so that when the nine key K^{59} is depressed the piece K^{71} will move a distance equal to one tooth of the rack R^{50} ; the piece K^{71} always moving a distance equal in number of teeth on the rack R^{50} to the complement of the number on the depressed key K^{59} .

As shown in Fig. 2, the seven key K^{59} is depressed and the type sector P^{54} is set to print the figure 7, but the rack R^{50} is moved to the rear a distance of only three teeth, which is the distance the piece K^{71} will move until its third step engages the depressed stop K^{24} on the keystem K^{59} .

In a machine of this type each column of keys acts in exactly the same way, and its mechanism is a duplicate in all respects of each of the other columns with the exception of the column at the extreme right-hand side, commonly known as the unit column. In the drawing in Fig. 1. and Fig. 2, the mechanism of the first or unit column is shown. This column of keys K^{59} must present for operation a series of stops K^{24} to limit the travel of the rack R^{50} after a movement equal to the complement in ten of the number on the depressed key K^{59} , but in all other columns it must be to the complement in 9 and this difference is accomplished by securing the small piece K^{73} farther to the rear on K^{71} by a distance equal to one tooth of the rack R^{50} that while the depression of the seven key K^{59} in the right-hand column causes the rack R^{50} to move a distance of three teeth, the depression of the seven key in all other columns will only cause the rack R^{50} to move a distance of two teeth. If no key K^{59} is depressed and the machine is operated with the subtraction key 70^K down, the rack R^{50} in the righthand col-

umn will move a distance of ten teeth, to allow which movement a small extra space "x" (Fig. 1.) is removed from the underside of the rack R^{50} at the front end. All of the other racks R^{50} will move to the rear a distance of nine teeth, but the pieces R^{53} will not move at all and consequently nothing will be printed, the type sectors P^{54} remaining in their normal position.

The mechanism and means to cause the different parts of this device to function properly in performing the act of addition and the printing of numbers are fully set forth in my British Patent No. 28253 of Dec. 28, 1908.

In order to maintain the pieces K^{71} and K^{72} in their proper position for engagement with piece R^{56} , it is necessary to lock them, while the machine is in use for purpose of addition, and a lock K^{74} is provided, which engages a small notch on the lower side of the piece K^{71} , and the other end of the piece K^{74} rests against the upper end of the piece R^{57} , so that when the piece R^{57} is moved to the position shown in Fig. 2, it disengages the lock K^{74} from the piece K^{71} .

Having described my invention I claim:

1. The combination in an adding and listing machine, of type for the printing of numbers, accumulators and a plurality of independently movable actuators for operating them, a plurality of sets of stops for limiting the movement of each actuator, one set of stops limiting the movement of the actuator to correspond to the number set up on the type for printing and the other set of stops limiting the movement of the actuator to correspond to the complement of the number set up on the type.

2. The combination in an adding and listing machine, of type for the printing of numbers, accumulators and a plurality of independently movable actuators for operating them, a plurality of sets of stops for limiting the movement of each actuator, one set of stops limiting the movement of the actuator to correspond to the number set up on the type for printing and the other set of stops limiting the movement of the actuator to correspond to the complement of the number set up on the type, and means under the control of the operator whereby the actuators may be made to engage the desired set of stops.

3. The combination in an adding and listing machine, of an accumulator and actuators therefor, type for the printing of numbers and a keyboard having keys for setting stops to limit the movement of the actuators, each key operating two stops, one of which will limit the movement of the actuator to correspond with the number on the key depressed and the other of which will limit the movement of the actuator to correspond

to the complement of the number on the key depressed and a selected device to cause the actuators to engage the desired set of stops.

4. The combination in an adding and listing machine, of an accumulator and actuators therefor, type for the printing of numbers, a keyboard for the setting of stops to limit the movement of the actuators and the type, each key operating two stops, one of which will limit the movement of the type and actuators to correspond to the number on the key depressed and the other of which will limit the movement of the actuator to correspond to the complement of the number on the key depressed, and means under the control of the operator to cause the accumulators to engage the desired set of stops.

5. In an adding machine, the combination with an accumulator, of independently shiftable controllers for each numerical order, each of said controllers carrying a plurality of stops, keys which are adapted to cooperate with the stops of both controllers of a given order, an accumulator-actuator for each order, and means for determining which of the stop-carrying controllers shall cooperate with the accumulator actuator.

6. In an adding machine, the combination with an accumulator, of an accumulator-actuator, an adding-controller, means normally coupling the accumulator-actuator and the adding-controller together, a subtracting controller, keys adapted to cooperate with the adding-controller and the subtracting-controller, and controllable means for coupling the subtracting-controller to the accumulator-actuator and disconnecting the adding-controller and accumulator-actuator.

40 7. In an adding machine, the combination with an accumulator, of an accumulator-actuator, an adding-controller, means normally coupling the accumulator-actuator and the adding-controller together, a subtracting controller, keys adapted to cooperate with the adding-controller and the subtracting-controller, a lock for normally securing the subtracting-controller, keys adapted to cooperate with the adding and subtracting controllers, and controllable means for unlocking the subtracting-controller and coupling it to the accumulator-actuator which also disconnects the accumulator-actuator and the adding-controller.

55 8. In an adding machine, the combination with an accumulator, of an accumulator-actuator, an adding-controller, means normally coupling the accumulator-actuator and the adding-controller together, a subtracting controller, keys adapted to cooperate with the adding-controller and the subtracting-controller, controllable means for coupling the subtracting-controller to the accumulator-actuator and disconnecting the adding-controller and accumu-

lator-actuator, and operating means for the controllers which has connections for restoring the controllers and the controlling means to their normal condition in relation to the accumulator-actuator.

70 9. In an adding machine, the combination with an accumulator, of an accumulator-actuator, an adding-controller, means normally coupling the accumulator-actuator and the adding-controller together, a subtracting controller, keys adapted to cooperate with the adding-controller and the subtracting-controller, a lock for normally securing the subtracting-controller, keys adapted to cooperate with the adding-controller and the subtracting-controller, controllable means for unlocking the subtracting-controller and coupling it to the accumulator-actuator which also disconnects the accumulator-actuator and the adding-controller, and operating means having connections for restoring the adding and subtracting controllers and the controlling means to their normal condition in relation to the accumulator-actuator.

80 10. In an adding machine, the combination with an accumulator, of an accumulator-actuator, an independent adding-controller, a toothed bar movably connected to the accumulator-actuator and adapted to normally engage the adding-controller so that said controller and actuator are coupled together for purposes of addition, an independent subtracting-controller, a toothed segment cooperating therewith which is normally disengaged from the toothed bar aforesaid, 100 keys adapted to cooperate with the adding and subtracting controllers to determine the extent of their movement, and controllable means adapted to disengage the adding controller and accumulator actuator and to engage the toothed bar with the segment to thereby place the accumulator-actuator under the control of the subtracting-controller.

110 11. In an adding machine, the combination with an accumulator, of an accumulator-actuator, an independent adding-controller, a toothed bar movably connected to the accumulator-actuator and adapted to normally engage the adding-controller so that said actuator and controller are coupled together 115 for purposes of addition, an independent subtracting-controller, a toothed segment cooperating therewith which is normally disengaged from the toothed bar aforesaid, keys adapted to cooperate with the adding and subtracting controllers to determine the extent of their movement, a lock for normally securing the subtracting controller against movement, and controllable means adapted to disengage the adding controller 120 and accumulator actuator and to release said lock and engage the toothed bar with the segment to thereby place the accumulator-actuator under the control of the subtracting-controller.

12. In an adding machine, the combination with an accumulator, of an accumulator-actuator, an independent adding-controller, a toothed bar movably connected to
5 the accumulator-actuator and adapted to normally engage the adding-controller so that said actuator and controller are coupled together for purposes of addition, an independent subtracting-controller, a toothed
10 segment coöperating therewith which is normally disengaged from the toothed bar aforesaid, keys adapted to coöperate with the adding and subtracting controllers to determine the extent of their movement, a
15 lock for normally securing the subtracting controller against movement, controllable

means adapted to disengage the adding controller and accumulator actuator and to release said lock and engage the toothed bar with the segment to thereby place the accumulator-actuator under the control of the subtracting-controller, and controller-operating means having connections adapted to restore all of the aforesaid parts to normal position.
